**CIRCUIT ARRANGEMENT FOR DETUNING
A CIRCUIT BY MEANS OF A SEMI-CONDUCTOR
BLOCKING DIODE**

Adalbertus Hermanus Jacobus Nieven van Dijkum and Cornelis de Vries, both of Nijmegen, Netherlands, assignors to North American Philips Company, Inc., New York, N.Y., a corporation of Delaware

Filed Sept. 6, 1960, Ser. No. 53,947

Claims priority, application Germany, Sept. 17, 1959,
N 17,257

2 Claims. (Cl. 334—15)

The invention relates to a circuit arrangement for detuning a circuit by means of a semi-conductor diode, driven in the reverse direction and controlled by a control-voltage. Such arrangements are used, for example, for the readjustment or for the modulation of the frequency of an oscillator. Such arrangements give rise to a problem in that the diode has, not only, a capacity varying with the control-voltage, but also an internal resistance varying with the control-voltage. This produces a variable damping of the resonant circuit, which damping varies with the amplitude modulation of the oscillations produced across the circuit.

The invention mitigates this disadvantage and is characterized in that the diode, shunted by a resistance of a suitable value, in series with a capacitor, is connected in parallel with the resonant circuit, which capacitor has a value such that the damping variation of the circuit is minimized.

The invention will be described more fully with reference to a drawing, which illustrates one embodiment. In the drawing the resonant circuit is designated by K. This circuit may be the frequency-determining circuit of an oscillator, of which the frequency is to be readjusted or modulated, or the circuit may be used in amplifiers having a variable tuning but a constant matching.

In parallel with the resonant circuit K is connected the series combination of a capacitor C and a diode D, shunted by a resistor R. The diode D is a semi-conductor diode and is biased in the reverse direction by a bias-voltage source V₀. In series with this bias voltage source V₀ is connected a control-voltage source V.

It is known that the internal capacity of the diode D varies in inverse proportion to the root of the applied voltage. However, it has been found that also the internal resistance of the diode varies with the applied voltage, so that a variable damping could occur in parallel with the circuit K. By providing the capacitor C and the resistor R, in accordance with the invention, and by suitable proportioning of these circuit elements the variation of this damping can be minimized. To this end the following relation should be fulfilled, approximately:

$$\omega^2 C^2 R R_d = \frac{C - C_g}{C_g}$$

2

wherein R designates the value of the resistor, C the capacity of the capacitor, ω the mean angular frequency of the resonant circuit, R_d the internal blocking resistance of the diode and C_g the mean capacity of the series combination of the capacitor and of the internal capacity of the diode.

What is claimed is:

1. A circuit for providing a variable reactance between first and second terminals comprising a capacitor and a semiconductor diode connected in series between said terminals, resistance means connected in parallel with said diode, means applying a variable reverse bias to said diode and means applying an oscillation between said terminals, the characteristics of said diode, capacitor, and resistance means being related substantially by the equation:

$$\omega^2 C^2 R R_d = \frac{C - C_g}{C_g}$$

wherein C is the capacitance of said capacitor, R is the resistance of said resistor, R_d is the internal blocking resistance of said diode, C_g is the mean series capacitance of said diode and capacitor, and ω is the angular frequency of said oscillation.

2. A resonant circuit having first and second terminals, and means for tuning said resonant circuit comprising a capacitor and a semiconductor diode serially connected between said first and second terminals, a resistor connected in parallel with said diode, a source of bias voltage connected to said diode to provide a reverse bias and control voltage means connected to said diode, said resistor, capacitor and diode satisfying the relationship:

$$\omega^2 C^2 R R_d = \frac{C - C_g}{C_g}$$

wherein C is the capacitance of said capacitor, R is the resistance of said resistor, R_d is the internal blocking resistance of said diode, C_g is the mean capacity of the series combination of said capacitor and diode, and ω is the angular resonant frequency of said resonant circuit.
